UNITED STATES PATENT OFFICE.

DUDLEY JAMES BARNARD, OF BARKING, ENGLAND.

GRAB.

1,353,651.

Specification of Letters Patent. Patented Sept. 21, 1920.

Application filed July 14, 1920. Serial No. 396,296.

To all whom it may concern:

Be it known that I, DUDLEY JAMES BARNARD, a subject of the King of Great Britain and Ireland, residing at 4 Strathfield Gardens, Barking, in the county of Essex, England, engineer, have invented certain new and useful Improvements in and Relating to Grabs, of which the following is a specification.

10 This invention relates to grabs of what is known as the single chain type, that is to say, a grab in which all movements are effected by means of a single chain or rope.

15 The objects of this invention are to simplify the general construction of the operative parts of the grab, to obviate any tendency on the part of the beam and power shaft to over-balance, and to more effectively guide said parts into correct position for engagement with the locking mechanism.

20 The invention further consists in the provision of an improved form of tipping mechanism by means of which the power shaft may be automatically disconnected from the bucket sections for the purpose of opening the buckets.

25 Broadly the invention consists of a pair of telescopic members arranged on each side of the grab, one part of each pair being carried by links mounted between the top cross members or bars and the other part by the cross beam. The rigidity of the spreader arms of the grab is further assured by the provision of a pair of links pivoted to the arms approximately at the top thereof.

30 The trip mechanism according to this invention consists of a lever, hereafter referred to as the trip lever, furnished at its upper extremity with a hook-shaped part adapted 40 to co-act with a tipping ring suspended by means of chains from a centralizing member carried by or hung from the jib of the crane.

35 The hook-shaped member is arranged to pass through the ring and when raised to the required extent, the ring is drawn under the hook by the action of the centralizing member. A vertically disposed link, pivoted to the other end of the trip-lever, co-acts with an extension on the gravity catch.

40 In the accompanying drawing which illustrates one embodiment of the invention:—

Figure 1 is a side elevation showing the bucket sections of the grab in closed position.

45 Fig. 2 is a front elevation of Fig. 1, cer-

tain parts being omitted to enable the essential features to be more clearly illustrated.

Fig. 3 is a similar view showing the bucket sections in open position, but with the power shaft in the normal position, with certain parts omitted.

50 In the drawings 1 and 2 are the bucket sections pivoted on independent pins 3, 4 on a cross beam 5; 6 and 7 are the top-cross bars and 8 the spreader arms, one at each outer corner of the bucket sections.

55 Supported by the top-cross bars 6 and 7 in any desired manner, such as by the plates 9, 10 spaced and held together by the bolts 11, is a set of purchase sheaves 12, mounted 70 on the spindle 13. The co-acting or power shaves 14, 15, are mounted on the spindles 16, 17 carried by the plates 18, 19, spaced and held together by the bolts 20.

60 The power shafts or studs 21, on which the gravity catches are mounted, are also carried on parts connected to the plates 18, 19.

65 The means for maintaining the normal balance of the operative parts comprises two 80 vertically disposed telescopic devices arranged one on each side of the grab, one member 23 of each device being carried by horizontally disposed plates or links 24, 25, mounted on the top-cross members 6 and 7, 85 the other member 26 of each device being carried by the parts 27 mounted on the cross beam 5, the said members 23, 26 passing through sleeves or thimbles 28, 29, carried by the plates 18 and 19 respectively. 90

70 Two of the spreader arms 8, one on each side of the grab, are furnished with extending portions 30, 31, to each of which, one end of a pair of links 32, 33 is pivoted, the other ends of such links being pivoted at 95 34 and 35 respectively, to the spreader arms at a point below the pivots for the arms on the top-cross bars.

75 The gravity catches which constitute the means for maintaining the bucket sections 100 1 and 2 in closed position are each provided with 3 operative parts, a catch or supporting hook 22, an extending lever 22^x and a projection 22^a. The hooks 22 are adapted to engage with the pins 36 carried by the parts 105 27 and the extending levers 22^x are adapted to co-act with the lower end of a lever 43. The projections 22^a are adapted to co-act with members 51 carried by vertically disposed members 52 sliding in guides 53, 110

mounted on the parts 28 and 29, said members 52 being controlled by springs 54, the top end of each spring being connected to the guides 53 and the lower end to the member 52. When the grab is closed or, until the power sheaves have been lowered for the purpose of closing the grab, the members 52 are depressed against the action of the springs 54 by stops 55 mounted on the plates 9 and 10. When the power sheaves are lowered, the action of the springs causes the members 51 to be brought up against the projections 22^a and thereby cause the hooks 22 to be drawn under the pins 36.

15 The trip mechanism according to this invention consists of a lever 37, furnished at its upper extremity with a hook shaped part 38 adapted to co-act with the inner edge 39 of tipping ring 40 suspended by means of 20 chains 41 from a centralizing member 42 carried by or hung from the jib of the crane.

The trip lever 37 is pivotally connected to the plate 9, and a further lever 43 is pivotally connected to its other end, which lever 25 is adapted to co-act with the gravity catches 22, so that when the trip lever is actuated by the tipping ring the gravity catches are depressed and released from the pins 36 and the bucket sections, having lost their means 30 of support, fall into the open position. The lever 43 is maintained in operative position with relation to the gravity catches by means of a pin 44 provided on the framework of the grab, said pin sliding in a slot 45 provided in the lever 43.

The centralizing member 42 above referred to is preferably of plate form and is provided with a centrally disposed thimble 46 through which the rope 47 is adapted to 40 pass.

To centralize the rope 47 with respect to the grab, a pair of horizontally disposed links or plates 48, 49, are mounted on the top-cross bars 6, 7, to which plates a two 45 part thimble 50 is bolted in any desired manner.

The thimble 50 is formed in two parts so that the eye on the extreme end of the rope may be passed through.

50 When the parts are in position shown in Fig. 1, and the entire grab is raised, the hooked end 38 of the trip lever is brought against the ring 40 which is thereby displaced laterally until it falls over the hook, 55 as shown by dotted lines in Fig. 1, under which it is drawn by the action of the centralizing member 42.

If the grab is now lowered, the resistance offered by the ring 40 causes the trip lever 60 37 to turn on its pivot and the lower end is forced downward against the lever forming an extension or part of the gravity catch which it depresses in the manner above referred to.

65 As the bucket sections fall, the tubular

members 26 slide downwardly over the members 23 and in the sleeves 28 29, until they occupy the position shown in Fig. 3.

By the arrangement above described it will be obvious that the parts must be 70 maintained in balanced position irrespective of the angle which the grab may take up while resting on a heap, the parts being by this means held in the correct position for engagement with the locking mechanism 75 when it is desired to close the grab.

I claim:—

1. In a grab of the kind herein described, the combination of means connecting the cross-beam the power shaft and the top 80 cross bars comprising two vertically disposed telescopic devices arranged one on each side of the grab one member of each device being carried by links mounted between the top cross bars and the other members 85 being carried by the cross beam and means for guiding said beam and said power shaft comprising sleeves or thimbles carried by the frame in which the power sheaves are mounted and adapted to form guides for 90 the telescopic members.

2. In a grab of the kind herein described, the combination of means connecting the crossbeam the power shaft and the top cross bars comprising two vertically disposed telescopic devices arranged one on each side of the grab one member of each device being carried by the links mounted between the top cross bars and the other members being carried by the cross beam, means for guiding 100 said beam and said power shaft comprising sleeves or thimbles carried by the frame in which the power sheaves are mounted and adapted to form guides for the telescopic members, means for locking said beam and 105 power shaft together, and means for disconnecting such locking means.

3. In a grab of the kind herein described, the combination of means connecting the cross-beam the power shaft and the top cross 110 bars comprising two vertically disposed telescopic devices arranged one on each side of the grab one member of each device being carried by links mounted between the top cross bars and the other member being carried by the cross beam, means for guiding said beam, and said power shaft comprising sleeves or thimbles carried by the frame in which the power sheaves are mounted and adapted to form guides for the telescopic 115 members, and means for centralizing the suspending rope with respect to the tipping ring comprising a plate having a centrally disposed two-part thimble through which the rope passes.

4. In a grab of the kind herein described, the combination of means connecting the cross-beam the power shaft and the top cross bars comprising two vertically disposed telescopic devices arranged one on each side of 130

- the grab one member of each device being carried by links mounted between the top cross bars and the other member being carried by the cross beam, means for guiding 5 said beam and said power shaft comprising sleeves or thimbles carried by the frame in which the power sheaves are mounted and adapted to form guides for the telescopic members, means for centralizing the suspending rope with respect to the tipping ring comprising a plate having a centrally disposed two-part thimble through which the rope passes, tipping mechanism comprising a ring suspended from the centralizing member and a lever having a hook-shaped part at its upper end adapted to co-act with the inner edge of said tipping ring, and means for imparting rigidity to the spreader comprising a pair of links each pivoted to the pair of spreader arms on one side of the grab the points of pivot of each link being respectively above and below the points of pivot of the pairs of arms to which they are connected. 55
5. In a grab of the kind herein described, the combination of means connecting the cross-beam the power shaft and the top cross bars comprising two vertically disposed telescopic devices arranged one on each side of the grab one member of each device being carried by links mounted between the top cross bars and the other member being carried by the cross beam, means for guiding 10 said beam and said power shaft comprising sleeves or thimbles carried by the frame in which the power sheaves are mounted and adapted to form guides for the telescopic members, means for locking said beam and power shaft together, and means for disconnecting such locking means. 15
5. In a grab of the kind herein described, the combination of means connecting the cross-beam the power shaft and the top cross bars comprising two vertically disposed telescopic devices arranged one on each side of the grab one member of each device being carried by links mounted between the top cross bars and the other member being carried by the cross beam, means for guiding 20 said beam and said power shaft comprising sleeves or thimbles carried by the frame in which the power sheaves are mounted and adapted to form guides for the telescopic members, means for locking said beam and power shaft together, means for centralizing the suspending rope with respect to the tipping ring comprising a plate having a centrally disposed two-part thimble through which the rope passes, and tipping mechanism comprising a ring suspended from the centralizing member and a lever having a hook-shaped part at its upper end adapted to co-act with the inner edge of said tipping ring. 25
